DESIGN FOR A COMBINATION DESK DRAWER AND SAFE

Irving Salomon, Michigan City, Ind.

Application April 16, 1942, Serial No. 106,587

Term of patent 7 years

To all whom it may concern:

Be it known that I, Irving Salomon, a citizen of the United States, residing at Michigan City, in the county of La Porte and State of Indiana, have invented a new, original, and ornamental Design for a Combination Desk Drawer and Safe, of which the following is a specification, reference being made to the accompanying drawing, forming a part thereof, in which:

Fig. 1 is a perspective view of a combination desk drawer and safe embodying my new design;
Fig. 2 is a top plan view; and
Fig. 3 is a rear elevational view thereof.

I claim:

The ornamental design for a combination desk drawer and safe, substantially as shown

IRVING SALOMON.
